COMPRESSOR REGULATOR

Lester L. Collins, Franklin, Pa., assignor to Chicago Pneumatic Tool Company, New York, N. Y., a corporation of New Jersey

Application July 7, 1939, Serial No. 283,289

12 Claims. (Cl. 230—31)

This invention relates to regulating apparatus for an air or gas compressor, particularly of the type which is equipped with unloading elements arranged to effect step-by-step loading and unloading in response to the demand on the storage tank or receiver.

Among the objects of the invention are: to make the unloading elements respond with a greater degree of sensitivity and dependability in operation to the pressure variations in the receiver; to insure against operation of the unloading elements simultaneously or in the wrong sequence; to permit quick and convenient adjustment of the range of the receiver pressure; and the provision of a regulator which is relatively simple in construction, low in manufacturing cost, and capable of operating over long periods without servicing.

In accordance with a feature of the present invention, the unloader, which controls the individual unloader elements, is supplied with fluid under transformed pressure which is related to, but varies to a much greater degree than, the receiver pressure. It is possible, therefore, to select a very narrow pressure range for the receiver while retaining the benefits of a broader range of pressure of the fluid that actuates the unloader.

In accordance with another feature of the invention, the secondary or transformed pressure is arranged to be varied inversely with the primary or receiver pressure. This expedient simplifies the design and arrangement of the unloader parts and further increases the sensitivity of the unloader by reducing the pressure acting on one face of the disc valve while the pressure increases on the opposing face.

Another feature is a novel pressure transformer designed to deliver fluid to the unloader under a pressure which has a wider range than the primary or receiver pressure.

Other objects and features of the invention will appear more clearly from the following description taken in connection with the accompanying drawings and appended claims.

In the accompanying drawings which illustrate one embodiment of the invention:

Fig. 1 is a plan view illustrating a fragmentary portion of a conventional compressor in association with an unloader and transformer designed and arranged in accordance with this invention;

Fig. 2 is a side elevational view of the transformer, unloader and pipes connecting these parts with each other and with the tank or receiver;

Fig. 3 is a side view, partly in elevation and partly in section, of the unloader;

Fig. 4 is a longitudinal sectional view of the transformer as indicated by the arrows 4 in Fig. 1;

Fig. 5 is an enlarged view, chiefly in longitudinal section, of certain parts of the transformer, including the valve mechanism that controls the size of the passageway through which the pressure fluid flows;

Fig. 6 illustrates the unloader and an inlet valve unloading element in longitudinal sections, as indicated by the arrows 6A and 6B respectively in Fig. 1, together with the connecting pipe; and

Fig. 7 is a chart showing the relationship between the receiver pressure and the secondary or transformer pressure.

For convenience, Figs. 1 and 2 are illustrated on a smaller scale than Fig. 3; Figs. 4 and 6 on a larger scale than Fig. 3; and Fig. 5 on a still larger scale.

The unloader U, shown in Fig. 1, is of the five-step type and comprises four sections UA, UB, UC and UD, arranged to deliver compressed air to pipes 11, 12, 13 and 14 in the order named to reduce the compressor load to $\frac{3}{4}$, $\frac{1}{2}$, $\frac{1}{4}$ and no load, respectively. These pipes may be connected to any suitable unloading device. By way of example, they are illustrated as connected to the inlet valve unloading mechanism mounted in the cylinder 15 of a two-stage compressor C, it being understood that the invention is equally applicable to single stage compressors.

The compressor C and unloading mechanism, illustrated in Fig. 1, are of the type which operate in accordance with a clearance and by-passing method of taking off and putting on the load in successive steps. In the first two steps, the load is varied by placing clearance chambers in continuous communication with the cylinders, thus reducing the volume of the intake by the expansion of previously compressed air from the clearance chambers into the cylinder. In the next two steps, the load is taken off by holding the inlet valves open continuously at the ends of the cylinder and oscillating the air as the piston reciprocates. Pipe 11, which is supplied with compressed air during the first and succeeding steps of unloading, is arranged to operate unloading device 16 to establish continuous communication between the crank end of the cylinder 15 and the clearance pocket 20 to reduce the load to $\frac{3}{4}$. The next pipe 12 operates unloading device 17 to open communication between the head end of the cylinder and clearance pocket 21 to

55

bring about a half-load condition. The next pipe 13 and associated unloader device 18 completely unload the crank end of the cylinder by holding the inlet valves open, thereby reducing the load to $\frac{1}{4}$. Pipe 14 and the associated unloading device 19 similarly vent the head end of the cylinder to effect a no-load condition. For a more complete description of this type of compressor and unloading apparatus, reference is made to Callan Patent 1,274,383, granted August 6, 1918.

The unloading element 16 is shown on a larger scale in Fig. 6. This element or device is associated with the inner and outer walls 22, 23 of the compressor cylinder 15, the inner wall having a stepped opening 24 therethrough in which an inlet valve assembly 25 of conventional plate type is mounted and retained in place by the usual holding members 26. To give access to valve chamber 27 for the insertion and removal of valve assembly 25, an opening 28 is provided in the outer cylinder wall 23. The valve lifter 29 is mounted upon valve assembly 25 to engage the plate valves 30 of the latter and to hold them open when the compressor cylinder is partially or entirely unloaded. The control apparatus by which valve lifter 29 may be actuated is supported over and may form a part of, or be supported by, the member which seals the opening 28 in the outer wall 23 of the compressor cylinder. The closure comprises a member 32 secured over opening 28 in any suitable manner as by a series of stud bolts 33.

Member 32 supports a cylindrical bracket 35 which receives a lifter actuating piston 36 with a sliding fit. Screws 37 secure bracket 35 to closure plate 32 and clamp therebetween the outer edges of a diaphragm 38. The diaphragm may consist of any suitable material such as a layer of rubber interposed between two layers of leather. The diaphragm forms one wall of a variable volume chamber 39 into which the pipe 11 discharges pressure fluid. The valve lifter 29 has an extension 40 projecting into the inner end of bracket 35 and secured to a rod 41, the outer end of which abuts against piston 36. The valve lifter 29 is yieldingly urged toward its outermost position, as illustrated, in which a shoulder on the lifter engages the inner end of the bracket 35. The yieldable means comprises a spring 42 interposed between the bracket and an abutment washer 43 on the rod.

It will be apparent to those skilled in the art that when the pipe 11 delivers fluid under considerable pressure to the chamber 39, the pressure on the outer face of the diaphragm will overcome spring 42 and move the piston 36, rod 41, and valve lifter 29 inwardly. Fingers 45 on the valve lifter then engage the inlet valves 30 forcing them off their seats against the pressure of valve springs 46 and establishing communication between the interior of cylinder 15 and the valve chamber 27 and clearance pocket 20. The valves 30 are held off their seats during both strokes of the compressor piston (not shown) as long as the pressure in chamber 39 is maintained. Unloader devices 17, 18 and 19 do not require detailed description as they are similar in construction to device 16, although the inlet valves on which devices 18 and 19 operate may connect the interior of the cylinder with atmosphere independently of any clearance pockets.

The unloader U which controls the supply of compressed air to the pipes 11, 12, 13 and 14 is illustrated most clearly in Fig. 3 and on the left

side of Fig. 6. It comprises an elongated base 49 at the bottom of which extends a longitudinal bore 50. One end of the bore is threaded to receive a pipe 51 from the receiver R while the other end is closed. Four uniformly spaced bores 52 extend upward from the inlet passage 50 to counterbores 53 opening at the upper surface of the base 49. Between the bore and the counterbore is an upwardly facing annular valve seat 54. The four counterbores are associated with unloader sections UA, UB, UC and UD, respectively. Each counterbore receives a body member 55 on the associated section with a snug fit. Spacer elements such as shims 56 are interposed between the upper face of the base 49 and an annular shoulder on the body member 55. Any desired means, such as vertical bolts 57 and horizontal bolts 58, may be employed for securing the body member 55 relative to the base 49.

The lower end of the body 55 terminates in an annular valve seat 60 somewhat larger in diameter than the lower seat 54 and is axially spaced therefrom. Counterbore 53 provides a valve chamber 61 which is divided into upper and lower compartments by a disc or plate valve 62. Valve 62 is formed with a reduced edge making a line contact with the wall of valve chamber 61 thus minimizing frictional resistance to its movement. Valve 62 is normally held in engagement with lower seat 54 to cut off the fluid supply from inlet bore 52. The holding means include a spring 64 disposed in body 55, the spring acting on the valve through a plunger 65 having a head 65a engaging the valve and provided with an abutment collar 65b for the spring. At its opposite end spring 64 engages the wall 66 forming an integral part of the body 55.

The lower part of the valve chamber 61 which surrounds the valve seat 54 is connected through bore 67 to a tapped opening 68 to which may be attached one of the pipes 11, 12, 13 or 14 leading to the compressor C. A check valve comprising a spring-pressed ball 69 may be interposed between the bore 67 and the outlet 68. The upper part of the valve chamber 61, which surrounds the upper seat is connected to the outlet opening 68 by way of a passage 69. It is also connected to a tapped opening 70 to which may be attached a pressure gauge or indicator 71.

When the unloader section UA is in the "load" condition, the receiver pressure acts against the lower face of the disc valve 62 over an area circumscribed by the annular seat 54 in opposition to the pressure of the spring 64 and supplemental holding means which will be described presently. Prior to the unloading operation the parts are in the position shown in Figs. 3 and 6 with the valve 62 held against its lower seat 54 and both the outlet pipe 11 and indicator opening 70 cut off from communication with the receiver pressure passage 50. When the receiver pressure rises above a predetermined amount, it overcomes the opposing spring and supplemental pressure to trip the valve 62 to its upper seat 60. The air pressure on the bottom of the disc acts over a greater area while the valve is in the upper position than when the valve engages the lower seat 54, the arrangement being such that the valve tends to remain in a stable condition according to its previous adjustment until there is a substantial change in pressure causing the valve to move. When the valve moves to upper seat 60 it connects the receiver pressure passage 50 through bore 52, around lower seat 54, through bore 67, past check valve 69 and through outlet

bore 68 to the pipe 11 leading to unloader device 15. Opening 10 associated with recess 61, admits air simultaneously to the gauge 71 which indicates that the compressor is in at least the first stage of unloading. Ball check valve 69 prevents fluttering of the disc valve 62 in a manner described more fully in Moody and Hoffman Patent 1,682,848, granted September 4, 1928. Further increase in receiver pressure trips the disc valves associated with unloader sections UB, UC and UD in the order named to effect $\frac{1}{2}$, $\frac{3}{4}$, and complete unloading, respectively, as hereinbefore described.

An important feature of the present invention resides in the provision of means for varying the pressure on top of the disc valve 62, as well as on the bottom, in response to pressure variations in receiver R. Accordingly, a diaphragm 75 is clamped between the upper face of the unloader section body 55 and a cover 76 forming a pressure chamber 77 above the diaphragm. The lower face of the diaphragm seats on a collar 78 at the upper end of rod 65, whereby the diaphragm pressure supplements that of spring 64 and opposes receiver pressure at the bottom of the disc valve 62. A pipe 79, leading from the transformer T, delivers transformed pressure fluid through branches 79a, 79b, 79c and 79d to the pressure chambers 77 in the unloader sections UA, UB, UC and UD, respectively. The transformer is so arranged that as the pressure in receiver R and on the bottom faces of disc valves 62 rises, the pressure in chambers 77 decreases, preferably to a greater degree.

The transformer T, which delivers transformer pressure fluid to pipe 79, is supplied with fluid under receiver tank pressure by a pipe 81. It comprises lower and upper casing sections 83 and 84 respectively, a gasket 85 between said sections, and bolts (not shown) for securing the sections together. The sections are recessed to provide a middle chamber 86 for reception of pressure fluid. The middle chamber is continuously vented through an outlet 87 under control of an adjustable needle valve 88. Chamber 86 is also continuously in communication through port 89 with outlet pipe 79 leading to unloader U. Compressed air is delivered to the middle chamber 86 from receiver R, pipe 81, inlet port 91, lower chamber 92 and central bore 93, the passage between the lower chamber and central bore being controlled by valve mechanism responsive to an increase in receiver pressure to reduce the rate of flow to the middle chamber 86 and vice versa.

The valve mechanism, as shown in Figs. 4 and 5, includes a valve cylinder 95, the upper end of which has a projection 96 seated in the central bore 93 and the lower end of which is seated in a recess 97 in a plug 98. A gasket 99 prevents leakage of pressure fluid from lower chamber 92 around the projection 96 to the middle chamber 86. Passage of pressure fluid from the lower to the middle chamber takes place through filter 101, ports 102 to the interior of the valve cylinder, through a passageway between a valve plunger 103 and a valve seat 104, and through a central opening 105 in the upper end of valve cylinder 95. Plunger 103 may be provided with circumferential grooves to receive lubricant and reduce the rubbing surface; and with a vertical groove (not shown) to equalize the pressure on the top and bottom of the plunger. A compression spring 106 tends to hold plunger 103 on, or near, the seat 104. It is opposed by pressure

responsive means acting against a pin 103a carried by the plunger 103 and extending into the middle chamber 86.

The pressure responsive plunger actuating means comprise a diaphragm 107 secured at its periphery between the upper casing section 84 and a hood 108 bolted to the casing. The hood encloses a pressure plate 109 seated on the diaphragm, a compression spring 110 engaging said plate, a spring button 111 at the upper end of the spring and a screw 112 for adjusting the tension of the spring. A lock nut 113 holds the screw in adjusted position. A push rod 114, bolted at its upper end to the pressure plate 109, extends downward into middle chamber 86 and abuts against the pin 103a on plunger 103. The push rod moves vertically in unison with the central part of the diaphragm 107 in response to pressure fluctuations at the bottom of the diaphragm.

The upper section 84 has a central opening providing an upper chamber 116 between the walls of the opening and a concentrically arranged bellows 117 surrounding push rod 114. The upper end of the bellows is secured to the central portion of the diaphragm 107. The lower end at its periphery is clamped between the section 84 and a closure plate 118 to seal the upper chamber 116, which surrounds the bellows, from the middle chamber 86 below and within the bellows. The upper chamber communicates, through passage 119, with pipe 120 supplying compressed air from receiver R.

Let it be assumed that the compressor C is operating under full load with the admission or rate of flow from the receiver R substantially balancing the supply by the compressor. Compression spring 110 in transformer T pushes down on diaphragm 107 and rod 114 to hold valve plunger 103 in spaced relation from valve seat 104 thereby admitting receiver pressure from lower chamber 92 to the middle chamber 86, which in turn is connected through pipe 79 to the chamber 77 in each of the sections in the unloader U. Receiver pressure in the upper chamber 116 of the transformer opposes spring 110 but is insufficient at this time to prevent the spring from holding the plunger 103 away from valve seat 104. The pressure fluid passing from lower chamber 92 to middle chamber 86 is balanced by air escaping through vent 87, and the parts remain in a state of equilibrium. In the unloader U, all disc valves 62 are held against their lower seats 54 in the "load" position by the spring 65 since the transformed pressure on top of the diaphragm 75 and the receiver pressure on the bottom of disc 62 almost balance each other.

Assume now that the demand on the receiver R diminishes, causing the pressure therein to rise gradually. Transformer spring 110 meets with increasing opposition by receiver pressure in upper chamber 116 permitting valve plunger 103, under the influence of spring 106, to approach more closely to the valve seat 104 and increasing the resistance to the flow of compressed air from the lower chamber 92 to the middle chamber 86. The resistance of the vent 87 being unchanged, the pressure in the middle chamber must drop causing a corresponding drop in the pressure on all of the unloader diaphragms 75. With the downwardly acting transformer pressure decreasing and the upwardly acting receiver pressure increasing, a point of equilibrium is passed and the disc valve 62 in

unloader section UA is tripped to its upper or "unload" position. In this position, receiver air is admitted to pipe 11 to actuate the first unloader device 16. If the receiver pressure continues to rise, the remaining unloader sections UB, UC and UD operate in the order mentioned to effect $\frac{1}{2}$, $\frac{3}{4}$ and complete unloading, respectively.

The pressures at which the respective disc valves trip are controlled by adjusting the springs 64 at different tensions. The spring tension may be regulated by the selection of shims 118 of desired thickness, between the spring 64 and collar 65b. Tightening the spring raises the required receiver pressure to operate the disc valve; loosening it lowers the required pressure. The lift of the valve 62 may be regulated by the shims 56.

Selection of receiver pressure is ordinarily effected by adjusting the screw 112 that abuts against the spring 110 in the transformer. Tightening the spring raises the receiver pressure, while loosening the spring lowers it. Operation of the unloader may be controlled by the vent needle valve 88 in the transformer. Closing the vent tends to retard operation of the unloader, while raising it tends to speed up the operation.

Referring to Fig. 7, it is seen that a slight variation in receiver pressure is accompanied by a large variation in transformer pressure. Among the advantages of using transformed pressure or a combination of receiver and transformed pressure, instead of receiver pressure alone, to actuate the disc valves, are that the unloader sections may be regulated to respond to the selected receiver pressures with a greater degree of accuracy and dependability, and that the unloader valves are assured of operation one at a time in the proper sequence.

In returning from the fully unloaded to the fully loaded condition, the unloader U operates step-by-step in the reverse order. As indicated in Fig. 7, the amount of receiver pressure necessary to trip an unloader section to "unload" position is considerably higher than the pressure at which the section is restored to loading condition. This is due to the arrangement of the differential pressure areas on the disc valve 62.

The bellows 117, and the parts to which it is attached, are so constructed that the bellows may be conveniently removed and replaced by another of different diameter. To obtain a close range of receiver pressure a bellows of relatively small diameter is employed; and a wider range is obtainable by the use of a larger bellows. According to an important feature of the invention, the lower part of diaphragm 107 is exposed to the pressure of upper chamber 116 outside of the bellows and middle chamber 86 within the bellows. As pointed out hereinbefore, the pressure in chamber 86 rises while the pressure in chamber 116 falls and vice versa. Increasing the diameter of the bellows transfers a part of the area at the bottom of the diaphragm from chamber 116 to chamber 86 and thus affects the range of receiver pressure.

What is claimed is:

1. In a pump or compressor having a receiver, a cylinder and a plurality of unloading devices arranged to effect step-by-step unloading of the compressor, automatic regulating means for said devices comprising an unloader having a series of pressure responsive valves controlling admis-

sion of pressure fluid to said unloading devices and having a series of pressure chambers controlling the operation of the valves, and a pressure transformer interposed between the receiver and the unloader pressure chambers to vary the pressure of the latter inversely with the receiver pressure.

2. In a compressor having a receiver, a cylinder and a plurality of unloading devices associated with the cylinder, an unloader for controlling the operation of the unloading devices, said unloader having a series of valves associated with the respective unloading devices, each valve being movable between two seats with a snap action, passages arranged to deliver fluid to the associated unloading device when the valve is in one position only, fluid pressure means corresponding to receiver pressure acting on the valve and tending to move it toward unload position, and opposed fluid pressure means tending to hold the valve in load position.

3. A compressor unloader comprising axially spaced upper and lower valve seats, the upper seat being of larger diameter than the lower, a disc valve movable between said seats with a snap action, a passageway arranged to be opened when the valve moves to its upper seat to deliver pressure fluid to an unloading device, means exposing the lower face of the valve to receiver pressure, a plunger acting on the upper face of the valve, a spring moving said plunger and valve downward, and means supplementing the action of the spring, the last-named means comprising a diaphragm connected to said plunger and a fluid pressure chamber above said diaphragm.

4. A compressor unloader according to claim 3 which includes means for varying the pressure in the diaphragm chamber inversely with the receiver pressure, whereby the downward pressure on the valve decreases and the upward pressure increases as the receiver pressure rises and vice versa.

5. In a fluid compressor regulator, a pressure transformer comprising a casing having an inlet port arranged to be connected to a pressure fluid receiver, an outlet port arranged to be connected to an unloader, a chamber in said casing in continuous and substantially unrestricted communication with the outlet port, a relatively restricted vent passage from said chamber, a passageway between said inlet port and said chamber, and automatic means responsive to receiver pressure for adjusting the size of said passageway and consequently the pressure in said chamber.

6. In a fluid compressor regulator, a pressure transformer comprising a casing providing a primary and a secondary chamber, means arranged to place said chambers in substantially unrestricted communication with a source of pressure fluid and an unloader respectively, a vent arranged to effect slow but continuous leakage of pressure fluid from said secondary chamber, a passageway between the primary and secondary chambers, a valve controlling the size of said passageway and consequently the pressure in the secondary chamber, said casing having a third chamber arranged to be supplied with fluid under pressure corresponding to receiver pressure, one wall of said third chamber being movable in response to pressure therein, and means connecting the movable wall with the valve to control the size of the passageway in response to receiver pressure.

7. In a fluid compressor regulator, a pressure

transformer comprising a casing providing a primary and a secondary chamber, means arranged to place said chambers in substantially unrestricted communication with a source of pressure fluid and an unloader respectively, a vent arranged to effect slow but continuous leakage of pressure fluid from said secondary chamber, a passageway between the primary and secondary chambers, a valve controlling the size of said passageway and consequently the pressure in the secondary chamber, said casing having a third chamber arranged to be supplied with fluid under pressure corresponding to receiver pressure, yieldable means moving the valve toward open position and fluid actuating means for the valve proportional to the pressure in the third chamber and opposing the yieldable means, whereby the secondary pressure varies inversely with the receiver pressure.

8. In a fluid compressor regulator, a pressure transformer comprising a casing providing a primary and a secondary chamber, means arranged to place said chambers in substantially unrestricted communication with a source of pressure fluid and an unloader respectively, a vent arranged to effect slow but continuous leakage of pressure fluid from said secondary chamber, a passageway between the primary and secondary chambers, a valve controlling the size of said passageway and consequently the pressure in the secondary chamber, said casing having a third chamber arranged to be supplied with fluid under pressure corresponding to receiver pressure, one wall of the third chamber being defined by a diaphragm, a spring acting on said diaphragm in a direction tending to reduce the size of the third chamber, and a push rod connecting the central part of the diaphragm with the control valve to regulate the position of the valve and the size of the passageway.

9. In a fluid compressor regulator, a pressure transformer according to claim 8 in which the diaphragm is on the side of the third chamber remote from the control valve and in which the push rod is surrounded by a bellows defining the inner wall of the third chamber.

10. In a pump or compressor having a receiver, a cylinder and a plurality of unloading devices

arranged to effect step-by-step unloading of the compressor, automatic regulating means for said devices comprising an unloader having a series of pressure responsive valves controlling admission of pressure fluid to said unloading devices and having a series of pressure chambers controlling the operation of the valves, and means for transmitting pressures from said receiver to said pressure chambers including a pressure transformer effecting wide pressure changes in said chambers in response to relatively small pressure changes in said receiver.

11. In a pump or compressor having a receiver, a cylinder and an unloading element associated with the cylinder, means for directing pressure fluid to said unloading element to operate said element, a valve movable to open and closed positions to control the flow of pressure fluid to said unloading element and adapted to prevent the flow of pressure fluid to said element when in closed position, spring means pressing said valve toward closed position, auxiliary means pressing said valve toward closed position, and means for increasing and reducing the pressure of said auxiliary means in a predetermined relation to the rise and fall of receiver pressure.

12. In a pump or compressor having a receiver, a cylinder and an unloading element associated with the cylinder, means for directing pressure fluid to said unloading element to operate said element, a valve movable to open and closed positions to control the flow of pressure fluid to said unloading element and adapted to prevent the flow of pressure fluid to said element when in closed position, a pressure chamber communicating with said receiver, means movable in response to pressure variations in said pressure chamber for moving said valve to closed position, a vent of reduced diameter connecting said pressure chamber to atmosphere, and means movable in response to pressure variations in said receiver for restricting the passage of pressure fluid from said receiver to said pressure chamber, said means acting to reduce the rate of flow to said chamber as the receiver pressure increases and to allow an increased flow as the receiver pressure drops.

LESTER L. COLLINS.
